ABSTRACT OF THE DISCLOSURE

Electrical connecting apparatus in the form of a readily transportable device which includes connector jaws arranged to be operated in a scissor-like fashion to establish electrical connection between a source of electricity and a resistive conductor wire embedded in a sealing strip of heat curable composition.

BACKGROUND OF THE INVENTION

In U.S. Pat. No. 3,574,024, it is proposed to use, in the manufacture of a motor vehicle on a factory production line, a method of bonding a window, for example a windscreens, in an aperture in the body part of the vehicle which method comprises applying to surfaces of the window or of marginal portions of the aperture a strip of material which is heat-curable to a resilient state and which has a resistive conductor of electricity extending lengthwise therethrough, electrically connecting the conductor with a supply of electricity, seating the window in the aperture so that the strip seals the gap between them and effecting curing of the material of the strip to a resilient state by passing an electric current through the conductor so that heat is generated therein, the strip thus being caused to bond to the window and to the body part and the window being seated in the aperture by pressing the window and body part together whilst the strip is soft. In carrying out this method, it has been proposed to connect the resistive conductor, in the form of a wire, with the supply of electricity by connector wires which carry "crocodile" clips which grip portions of the strip. In order to ensure adequate curing of the strip in carrying out this method, the material of the strip is removed at each end portion of the strip to bare the end portions of the wire in order to facilitate electrical contact between the clips and the conductor wire. However, occasionally satisfactory electrical contact may not be made between the clips and the wire.

SUMMARY OF THE INVENTION

It is one of the various objects of the present invention to provide apparatus which can be used in a motor vehicle factory production line for electrically connecting a resistive conductor wire, extending through a strip of heat-curable material used for bonding a window in an aperture of a motor vehicle body part, with a supply of electricity.

Accordingly, the invention provides in one of its various aspects apparatus comprising a support, jaw assemblies mounted on the support, each jaw assembly comprising first and second jaw elements, each element comprising a knife edge portion and one of the elements of each jaw assembly comprising an electrically-conductive portion, the apparatus comprising means whereby when a portion of a resistive conductor wire is gripped in electrical contact with the electrically-conductive portion of the assembly relative movement may be brought about between the elements of the assembly so that the knife-edge portions exert a shearing action on the wire which is sufficient to establish electrical contact between the wire and the electrically-conductive portion but is not sufficient to

2

sever the wire, one of the elements of each jaw assembly being shaped so as to retain the portion of the wire in electrical contact with the electrically-conductive portion of the assembly when the portion of the wire is gripped between the knife-edge portions, and means for electrically connecting the electrically-conductive portion of each assembly with a supply of electricity.

We prefer that the knife edge portion of the first jaw element of each assembly is spaced from the knife edge portion of the second jaw element thereof in a first direction which extends heightwise of the elements, the elements being mounted so that their knife-edge portions can be moved relative to each other in a second direction which extends at least substantially perpendicular to said first direction so as to grip said portion of the resistive conductor wire.

There are preferably two jaw assemblies, the second elements of the assemblies being connected with means for moving the second elements simultaneously away from their respective first elements to allow placement of portions of the electrically-conductive wire in positions so that they can be gripped in the jaw assemblies. Preferably the means for moving the second elements comprises link members which are pivotally fastened to a rotatable member and to the second elements, the rotatable member being mounted on a pin which is secured to the support; more preferably the second element of each assembly is urged to move by a spring which is mounted on the pin and is arranged to urge the rotatable member to rotate.

Preferably the second element of each assembly in an apparatus as set forth in the last preceding paragraph but two is substantially S-shaped and is pivotally secured upon the first element, the first element being secured to the support. Preferably the first element of each assembly provides the electrically-conductive portion thereof. We prefer that the first and second elements of each assembly are provided by first and second metal blades.

In an apparatus as set forth in the last preceding paragraph but three we prefer that the electrically-conductive portion of each assembly is connected with the supply of electricity through a switch mounted on the support. Preferably means is provided for visually indicating completion of an electrical circuit between the electrically-conductive portions of the assemblies.

There now follows a detailed description which is to be read with reference to the drawings accompanying the specification; it is to be clearly understood that the illustrative apparatus and the illustrative method have been selected for description to illustrate the invention by way of example and not by way of limitation.

DESCRIPTION OF THE DRAWINGS

FIG. 1 is a plan view, with parts broken away, of the illustrative apparatus;

FIG. 2 is a view partly in section of the illustrative apparatus viewed in the direction of the arrow A in FIG. 1; and

FIG. 3 is a view of the illustrative apparatus viewed in the direction of the arrow B in FIG. 2.

DESCRIPTION OF THE ILLUSTRATIVE APPARATUS AND METHOD

The illustrative apparatus is intended for use in connecting a resistive conductor wire which extends through a strip of material which is heat-curable to a resilient state and which in its cured condition bonds to glass and to primed metal surfaces, with a source of electricity in carrying out the illustrative method which is a method of bonding a windscreens in an aperture therefor provided in a vehicle body using the strip of material. Examples of strips of material having a resistive conductor wire ex-

tending therethrough are disclosed in the above recited patent.

The illustrative apparatus comprises a support in the form of a casing comprising a first casing part 10 and a second casing part 11 which are secured together by screws (not shown); a handle 12 is provided on the second casing part 11. The casing parts 10 and 11 and the handle 12 are made of thermoplastic material, the casing parts 10 and 11 being formed by a rotational moulding process. Two jaw assemblies, generally indicated at 14 and 16, are mounted on the support, and each jaw assembly comprises a first jaw element in the form of a flat, metal, blade 18 which is secured to the first casing part 10 and a second jaw element in the form of a flat, substantially S-shaped, metal, blade 20. The blades 18 and 20 each comprise a knife-edge portion 19, 21 respectively and are partially enclosed within guard members 22 and 24, the guard member 22 being integrally formed with the first casing part 10 and the guard member 24 being integrally formed with the second casing part 11. The two blades 18 and 20 of each jaw assembly 14 and 16 are maintained in spaced-apart parallel relationship in a first direction extending heightwise of the blades by a spacer element 28 on a pin 26 such that the blade 20 can pivot about the axis of the pin in a second direction (clockwise or anti-clockwise) extending perpendicularly to the first direction; the knife-edge portion 19 of the blade 18 of each assembly is spaced from the knife-edge portion 21 of the blade 20 by a distance which is not greater than a minimum width of cross-section of a portion of the resistive conductor wire, the construction and arrangement being such that the knife-edge portions 19 and 21 exert a shearing action upon the portion of the wire which action is sufficient to cause the knife-edge portions to bite into the portion of the wire but is not sufficient to sever the wire. Each pin 26 extends through apertures provided in the two guard members 22 and 24. Each blade 18 is held in spaced-apart relationship relative to the guard member 24 by a sleeve 30 carried in the pin 26, and each blade 20 is maintained in spaced-apart relationship relative to the guard member 22 by a sleeve 32 carried on the pin.

The head 34 of each pin 26 of the illustrative apparatus is urged against a collar member 36 carried by the pin between the head 34 and the guard member 24 by an internally threaded cap 38 which is threadedly engaged upon a threaded end portion of the pin 26 remote from the head 34, and is tightened upon the threaded end portion of the pin with the guard member 22 held between the cap 38 and the sleeve 32. The two blades 20 of the jaw assemblies 14 and 16 of the illustrative apparatus are pivotally connected on stub shafts 40 with means for moving them about the axis of the pins 26 whereby to open the two jaw assemblies simultaneously, the means comprising link members 42 which are of an electrically non-conductive material and which are pivotally fastened upon a rotatable member in the form of a disc 44 of an electrically non-conductive material by pins 46 which have screw-threaded end portions threadedly-engaged in threaded recesses in the disc 44. The two pins 46 extend into bores of a cylindrical bush 48 and are each threadedly engaged in an internally-threaded lining 50 of each of their respective bores. The bush 48 extends through an aperture in the guard member 24 and is provided with a handle portion 52 of the means for moving the second elements. The disc 44 is supported in spaced-apart relationship relative to the guard member 22 by a headed stud 54 which extends through a central aperture in the disc and has a threaded recess in which is threadedly engaged a screw 56, the shank of the screw extending through an aperture in the guard member 22 so that the guard member 22 is clamped between the head of the screw and the stud 54. A coiled spring 58 is supported on the stud, end portions of the spring being held by the disc 44 and guard member 22 respectively, the construction

and arrangement being such that, viewing FIG. 1, the spring 58 urges the disc 44 and the bush 48 to rotate in a clockwise direction to a limit position which is determined by a stop member 60 of the disc 44 against which the two members 42 abut.

The two blades 18 of the jaw assemblies 14 and 16 of the illustrative apparatus are connected electrically, in a circuit which includes a control switch 62, with a supply of electricity; means in the form of an indicating lamp 64 is provided in the circuit for providing visual indication of completion of the circuit between the first blades 18 of the two assemblies. Two water spray tubes 65 which are directed towards the knife-edge portions 19 and 21 of the blades 18 and 20 are connected with a water reservoir provided in the casing of the apparatus and a plunger 66 of a plunger assembly is provided for forcing water through the tubes 65 and onto the blades 18 and 20. The construction and arrangement of the plunger assembly is such that the plunger 66 cannot be pressed while the electric circuit is closed.

In carrying out the illustrative method of bonding a windscreens in an aperture therefor provided in a vehicle body on a motor vehicle factory production line, the illustrative apparatus is suspended from about the production line in such a manner that the apparatus can be positioned on the roof of the car in preparation for carrying out the method. In carrying out this method the strip of material in an uncured condition is positioned between primed surface portions of the aperture and the windscreens with end portions of the strip crossed over. The windscreens is seated in the aperture and is pressed into position, whilst the strip is soft and before the material of the strip has cured to a resilient state, so that the strip seals a gap existing between the marginal surfaces and the windscreens. The end portions 68 and 70 of the strip are gripped between the knife-edge portions 19 and 21 of the blades 18 and 20 respectively of the jaw assemblies 14 and 16 of the apparatus by first moving the handle portion 52 in an anticlockwise direction (viewing FIG. 1) against the force of the spring 58 to pivot the blade 20 of each jaw assembly about the pin 26 thereby to open the jaw assembly. The end portions 68 and 70 of the strip are then placed between the blades of the jaw assemblies 14 and 16 respectively and the handle portion 52 is released so that the spring 58 urges the disc to return to its limit position so that the knife-edge portions 19 and 21 of the blades of the jaw assemblies firmly grip the end portions 68 and 70 of the strip, the end portions 68 and 70 being prevented from slipping from the jaw assemblies by the curved blades 20. Because the blades 18 and 20 are spaced apart by a distance which is less than the minimum width of cross-section of the end portions of the wire, the end portions of the strip are twisted between the blades as shown in FIG. 3 and the knife-edge portion 21 of each blade 20 and the knife edge portion 19 of each blade 18 shear through the uncured heat-curable material of the strip to the conductor wire of the strip and bite into the metal of the wire so that the conductor wire is in electrical contact with the blades 18 and 20 of the two assemblies. The switch 62 is then closed and the electrical circuit is completed from the supply of electricity through the conductor wire of the strip, completion of the circuit being indicated by glowing of the element of the lamp 64. The conductor wire is heated by the electric current and the heat-curable material of the strip is heated by the wire thus causing the material to cure to a resilient state. The end portions of the strip are then released from the jaw assemblies of the illustrative apparatus and are then either cut off or are inserted into a windscreens reveal moulding which is applied after bonding.

When the illustrative apparatus is used for connecting the resistive conductor wire of the strip of heat-curable material in carrying out a method as described in the last preceding paragraph, the material of the strip can be inhibited from adhering to the blades 18 and 20 of the jaw

assemblies by spraying water onto the blades from the reservoir provided in the casing of the apparatus by pressing the plunger 66.

Having thus described our invention, what we claim as new and desire to secure by Letters Patent of the United States is:

1. Apparatus for connecting an electrically conducting wire with a supply of electricity comprising a support, a jaw assembly mounted on the support, said jaw assembly comprising first and second jaw elements spaced in first and second substantially perpendicular directions from each other, each element having a knife edge portion and one of the elements has an electrically conductive portion, means for moving one element relative to the other so that the knife edge portions of each element cooperate to exert a shearing action on the wire placed between the elements which is sufficient to establish electrical contact between the wire and the electrically conductive portion but is not sufficient to sever the wire, and means for electrically connecting the electrically conductive portion with a supply of electricity.

2. Apparatus according to claim 1 wherein there are two jaw assemblies and the second elements thereof are each connected with said means for relatively moving the elements, the said means being arranged so that the second elements may be moved simultaneously away from their respective first elements to allow placement of portions of the electrically conductive wire in positions so that the wire can be gripped in the jaw assemblies.

3. Apparatus according to claim 1 wherein said means

for moving the second elements comprises link members which are pivotally fastened to a rotatable member and to the second element, the rotatable member being mounted on a pin which is secured to the support.

5. Apparatus according to claim 3 wherein a spring is mounted on the pin and is arranged to urge the rotatable member to rotate to move the second element to a spaced position relative to the first element.

10. Apparatus according to claim 1 wherein the second element is substantially S-shaped for retaining the wire in electrical contact with the conductive element portion and is pivotally secured upon the first element, the first element being secured to the support.

15. Apparatus according to claim 1 and additionally comprising means electrically connected to the element conductive portion for visually indicating completion of an electrical circuit between the wire and the supply of electricity.
